DESIGN FOR AN ARCH-STREAM OFFSET
COMBINATION FAUCET STRUCTURE

Albert G. Smolensky, Cleveland, Ohio

Application October 5, 1946, Serial No. 133,788

Term of patent 14 years

(Cl. D91—3)

To all whom it may concern:

Be it known that I, Albert G. Smolensky, a citizen of the United States, residing at Cleveland, in the county of Cuyahoga and State of Ohio, have invented a new, original, and ornamental Design for an Arch-Stream Offset Combination Faucet Structure, of which the following is a specification, reference being had to the accompanying drawing, forming part thereof.

The single figure of the drawing is a perspective view showing my new design of an arch-stream offset combination faucet structure.

I claim:

The ornamental design for an arch-stream offset combination faucet structure, as shown.

ALBERT G. SMOLENSKY.
